UNITED STATES PATENT OFFICE.

FRANK SCHWARTZ, OF NEW YORK, N. Y.

BEAM COMPASS.

Application filed May 17, 1926. Serial No. 109,616.

This invention relates generally to drafting instruments and more particularly to beam compasses.

An object of the present invention is to provide in connection with the commonly used beam, improved means for clamping thereto the pivot pin or needle, and other clamping means for selective engagement of the instruments of the drawing set, such as an ordinary bow-pencil or bow-pen. One of the principal features of the invention lies in providing, in connection with a beam of the class described, means whereby bow-pens or bow-pencils having spring arms of varying widths may be selectively accommodated and rigidly held in position, said means engaging only the pivot pin arm of the selected instrument, the pencil or pen arm being free to be adjusted by the usual thumb nut or the like.

Another feature of the invention resides in a novel construction of means for carrying and locking the pivot point at a desired point along the beam.

A further feature resides in the provision of a clamping plate or engagement member for retaining a selected bow-pen in tilted operative position wherein the pen rests on the paper while the opposite pivot-pin is held elevated therefrom.

In the drawings:

Fig. 1 is a side elevation of an improved beam-compass with the clamping devices in position.

Fig. 2 is an enlarged section on the line 2—2 of Fig. 1.

Fig. 3 is a detail perspective of an improved clip plate or engagement member.

Figs. 4 and 5 are elevational and end sectional views respectively of a modified form of clamping device.

Referring to the drawings, on the beam 10 is carried a pivot pin 11, and a bow pen 12, of the usual form. In carrying out my invention, I provide means for holding the pivot pin arm 13 of the bow pen in rigid relation with the beam while the pen arm 14 of said bow pen is free to be adjusted by the thumb nut 15. The different makes of bow pens available on the market have arms of different widths and to accommodate these various sizes, I provide a clip plate or engagement member, comprising an integral blank having a medial body portion 17 and crimped instrument-accommodating ends. The latter are constituted of angularly bent ends 18 and 19, portions 22 and 23, and terminal flanges 24 and 25, which construction forms grooves 26 and 27 to receive the arm 13 of the bow pen.

The instrument-engaging member is accommodated in a sleeve element 28 loosely and slidably encircling the beam 10. The instrument-engaging member is clamped in position against the beam with one crimped end clamping the arm 13 of the bow pen against the beam, by means of a thumb screw 29 engaging in a threaded bore in the element 28, as shown, and permitting a certain play between the instruments engaging member and the sleeve 28 to accommodate various sized instruments of a drawing set such as the bow pen 12.

As shown in Figs. 1 and 3 of the drawings, the channeled crimped ends are arranged with the channels at an angle to the longitudinal center of the engagement member so that the arm 13 of the bow pen is held at an angle to the perpendicular, while the pen arm 14 of said bow pen may operate at 80 the perpendicular or substantially so, as the thumb nut is adjusted in the operation of the instrument.

As clearly shown in Fig. 2, the channel 27 is deeper than the channel 26 to accommodate bow pens with wider arms, as will be readily understood. I will also call attention to the fact that—as shown in Fig. 2—the channels 26 and 27 are much wider than the thickness of the clamped pen arm. This 90 also is to permit of a wide range of adjustment in the thickness of the pens received by my device and in their angles to the vertical.

The pivot pin 11 is preferably soldered, 95 or otherwise secured to an engagement member 30, the latter having a turned up end 31 to confine it in a sleeve element 32 which encircles the beam 10 and is clampable to the beam by a thumb-screw 33. Pin 11 may 100 also have an upward extension handle 11^a to facilitate the manipulation of the beam compass.

In the construction shown in Figs. 4 and 5 of the drawings, there is shown a strap 34, 105 which is bent around the beam 10 and over the medial body portion 17 of the instrument engaging member, the strap terminals forming spaced ears 35, through which a thumb screw 36 passes into engagement with 110 a nut 37, to clamp the engagement member in position on the beam.

The operation and utility of the beam compass constructed as above set forth will be apparent without further description and while there are illustrated preferred embodiments of the invention, it will be obvious that the structural elements thereof are susceptible to such further variations and modifications as fall within the scope of the appended claims.

10 What I claim as new, is:—

1. In a beam compass, a beam, an engagement member comprising an integral blank having a medial body portion and crimped ends for selective accommodation thereunder and against the beam of instruments of a drawing set, and a clamping device for said member, said device comprising a sleeve element slidably engaging about the beam and adapted to accommodate said body portion between one side thereof and one side of the beam so as to hold and engage the instrument against the beam, and means for simultaneously securing said body portion to the clamping device and to the beam.
- 15 2. In a beam compass, a beam, an engagement member comprising an integral blank having a medial body portion and crimped ends for selective accommodation thereunder and against the beam of instruments of a drawing set, and a clamping device for said member, said device comprising a sleeve element slidably engaging about the beam and adapted to accommodate said body portion
- 20
- 25
- 30

tion between one side thereof and one side of the beam so as to hold and engage the instrument against the beam, and means for simultaneously securing said body portion to the clamping device and to the beam, said last named means comprising an adjustable threaded element associated with the clamping device and adapted to bear against said body portion and through the latter against the beam to force one side of the sleeve element against one side of the beam.

3. In a beam compass, a beam, an instrument-engaging member comprising an integral blank having a medial body portion and crimped instrument-accommodating ends, and a clamping device for securing said member in desired position along the beam, said clamping device comprising a sleeve element having a threaded bore and slidably engaging about the beam, said sleeve element being adapted to accommodate said body portion beneath said bored side, and a threaded element mounted in said bore and engaging said body portion, whereby adjustment of the threaded element will frictionally grasp the beam between said body portion and the opposite side of the sleeve element.

Signed at New York, in the county of New York, and State of New York, this 8th day of May, A. D. 1926.

FRANK SCHWARTZ.
